CLAIM

The ornamental design for a hair brush with ejectable barrel, as shown and described.

DESCRIPTION

FIG. 1 is a rear perspective view of a hair brush with ejectable barrel showing my new design.

FIG. 2 is a front perspective view thereof.

FIG. 3 is a front elevational view thereof.

FIG. 4 is a rear elevational view thereof, the rear elevational view enlarged for clarity.

FIG. 5 is a right side elevational view thereof, the left side elevational view being a mirror image of the right side elevational view.

FIG. 6 is a top plan view thereof, the bottom plan view being a mirror image of the top plan view.

FIG. 7 is an exploded perspective view showing the handle ejected from the barrel, the exploded perspective view illustrating an ejection mechanism of my design.

FIG. 8 is another exploded perspective view showing the handle ejected from the barrel.

FIG. 9 is a front elevational view of the handle and the barrel, the barrel being ejected from the handle in this view, the front elevational view enlarged for clarity.

FIG. 10 is a rear elevational view of the barrel and the handle, the barrel being ejected from the handle in this view, the rear elevational view enlarged for clarity.

FIG. 11 is a partial perspective cross-sectional view taken along line 13-13 of FIG. 10, the view enlarged for clarity.

FIG. 12 is a partial perspective view, enlarged for clarity, showing the connection mechanism of the handle portion.

FIG. 13 is a partial elevational cross-sectional view taken along line 13-13 of FIG. 10, the view enlarged for clarity.

FIG. 14 is a partial elevational sectional view taken along line 14-14 of FIG. 9, the view enlarged for clarity.

FIG. 15 is a partial perspective sectional view taken along line 15-15 of FIG. 9, the view enlarged for clarity; and, FIG. 16 is a partial perspective sectional view taken along line 16-16 of FIG. 9, the view enlarged for clarity.

The broken lines shown in the enlarged partial perspective views of FIGS. 12-16 show the bounds of the enlarged views and do not form part of the claim. The barrel of the hair brush may be connected to and ejected from a variety of different brush heads.

The broken lines in the drawings depict features that form no part of the claimed design.

1 Claim, 10 Drawing Sheets
